L. F. CUTLER.

LEATHER WORKING MACHINE.
APPLICATION FILED SEPT. 4, 1917.

1,267,853.

Patented May 28, 1918.

Fig. 1.

UNITED STATES PATENT OFFICE.

LEWIS F. CUTLER, OF SALEM, MASSACHUSETTS, ASSIGNOR TO THE TURNER TANNING MACHINERY COMPANY, OF PEABODY, MASSACHUSETTS, A CORPORATION OF MAINE.

LEATHER-WORKING MACHINE.

1,267,853.

Specification of Letters Patent. Patented May 28, 1918.

Application filed September 4, 1917. Serial No. 189,467.

To all whom it may concern:

Be it known that I, LEWIS F. CUTLER, a citizen of the United States, and a resident of Salem, in the county of Essex and State of Massachusetts, have invented an Improvement in Leather-Working Machines, of which the following description, in connection with the accompanying drawings, is a specification, like characters on the drawings representing like parts.

This invention relates to machines for treating hides, skins and leather of that class in which a working tool is reciprocated lengthwise of the bed upon which the work is supported, and in which the bed is automatically maintained under tension.

The invention has for its object to provide a machine of the character referred to, in which a bladed cylinder may be used as the reciprocating tool and act on the work in a superior manner and in some cases perform a kind of work now performed by hand, as will be described.

To this end the machine is provided with a bed having novel features as will be described.

Figure 1 represents a sufficient portion of a hide and leather working machine embodying this invention to enable the same to be understood.

Fig. 2, an end elevation of the machine shown in Fig. 1 looking toward the left, and

Fig. 3, an enlarged cross section on the line 3—3, Fig. 1.

Referring to Fig. 1, *a* represents a bladed cylinder or operating tool such as now commonly used in hide and leather working machines, and which co-operates with and is reciprocated in any suitable manner lengthwise of a bed or support *b* for the hide, skin or leather.

The bed *b* comprises essentially a strip or apron 10 of flexible material, such as canvas, which is fastened at one end as by screws 12 or otherwise to a stationary member or frame work, comprising a casting or metal plate 13 having near its opposite ends pairs of uprights 14, 15, which support rollers 16, 17, over which the strip or apron 10 is passed to form a substantially horizontal working section 18 between said rollers, said strip being attached as by screws 19 or otherwise to a roller 20, rotatably mounted

in brackets or arms 21 attached to the casting or plate 13 and forming part of the bed frame. As shown in Fig. 1, the arms 21 are inclined downward from one end of the casting or plate 13 and the strip 10 is passed under the roller 20 and secured to the latter above the horizontal center of its shaft 22. The flexible strip 10 is automatically maintained under tension, which is accomplished in the present instance by means of weights 23, adjustably mounted on levers or arms 24 fastened to the shaft 22. The tension of the strip 10 may be regulated by moving the weights 23 lengthwise on the arms or levers 24 and the weights may be secured in their adjusted position by suitable set screws 25 or otherwise. The working section 18 of the strip or apron 10 has co-operating with it a substantially rigid member 26, preferably a steel plate, which is of a length substantially equal to the length of the working section 18, and upon which the latter rests. The plate 26 is free to move bodily in a direction substantially at right angles to the length of the working section 18 of the strip 10, and to this end it is yieldingly supported, which may be accomplished in any suitable manner, and in the present instance, is shown as resting on a cushion 30 of rubber or other resilient material, which is located as hereinabove shown at the longitudinal center of the plate 26 and is supported by a suitable upright 31, on the bed frame 13. The plate 26 also has co-operating with it means for rendering it fixed or stationary temporarily for a purpose as will be described, and in the present instance, said means are shown as a plurality of screw-threaded rods 32, which are extended up through the bed plate or frame 13 and may be turned in one direction to bring them up into contact with plate 26 to rigidly support it and prevent downward movement thereof, or they may be turned in the opposite direction to remove them from engagement with said plate and thereby permit the latter to be moved downward.

The screws 32 in their lowered or withdrawn position may also act as stops to limit the downward movement of the plate 26, and may be secured in their adjusted positions by nuts 33 co-operating with the frame 13.

The working section of the strip or apron

10 may have the hide, skin or leather, not shown, placed directly upon it, but it is preferred to provide the said working section with a bolster of any suitable or usual material and which is herein represented as a layer 35 of rubber resting on and preferably vulcanized to the strip 10 and a layer 36 of leather covering said rubber layer, the leather covering being fastened at its front 10 end to the strip 10 by suitable devices 37.

The hide, skin or leather to be treated is laid upon the bolster 36, 35, and is subjected to the action of a working tool, preferably the bladed cylinder or roll *a*, such as now 15 commonly employed in hide and leather machines and which is represented by the dotted line circles in Fig. 1.

The bladed cylinder *a* is reciprocated lengthwise of the bed by suitable mechanism, not shown, but which may be such as now commonly employed in machines for whitening and buffing leather, an example of which is disclosed in U. S. Patent No. 631,359 dated August 22, 1899.

25 The bladed cylinder *a* is moved from the front to the rear of the bed in a substantially horizontal plane, indicated by the line 40, and is returned in the plane indicated by the line 41.

30 The bladed cylinder *a* on its forward movement indicated by the arrow 42 acts on the upper surface of the work laid upon the bolster 36, 35, and on its return movement is out of contact with the work.

35 After the path of movement of the bladed cylinder *a* has been determined, the screws 32 are turned up to engage the plate 26 and rigidly support the same, and the bolster 36, 35, is trimmed, cut by the bladed cylinder 40 so as to conform to the path of forward movement of the bladed cylinder indicated by the line 40. The screws 32 are then backed off to permit the bed and the leather thereon to yield more or less under the action 45 of the bladed cylinder *a* on the forward or active stroke of the latter.

The rear end of the apron or strip 10 is free to move according to the pressure placed upon the work by the bladed cylinder and 50 a constant tension is maintained upon the apron or strip 10 irrespective of the variation in thickness of the work by the weighted levers 24, which are raised by the rotation of the shaft 22 and roller 20 under the influence of the pressure of the working tool *a* upon the work on the bolster 36, 35.

The plate 26 acts to distribute the pressure of the bladed cylinder *a* lengthwise of the working section 18 of the flexible strip 60 or apron 10, and the yielding support for the plate and working section of the flexible bed acts to equalize the resistance of the bed so as to obtain a uniform or substantially uniform depth of cut in the work over 65 an uneven surface.

A bed embodying this invention enables the machine in which it is employed to buff leather and especially highly stuffed leather on the grain side, which now is accomplished only by the use of hand-operated slickers 70 so far as I am aware.

Also a material saving of leather is obtained, for in the old method of hand buffing on the grain side as much as twenty-eight per cent. by weight of material is removed, 75 whereas with a machine provided with my improved bed, only from fifteen to eighteen per cent. was taken off in the buffing operation.

Furthermore the leather is given a finer 80 surface. So also, light weight leather can be whitened with the machine.

I have herein shown one embodiment of the invention, but it is not desired to limit the invention to the particular construction 85 shown.

Claims:

1. In a machine of the character described, in combination, a flexible bed fastened at one end and having its opposite end free to 90 move, means connected with said free end to place the flexible bed under tension and to maintain the latter substantially uniform, a rigid member located under said flexible bed and coöperating therewith to move bodily 95 with the flexible bed under the action of a working tool, means coöperating with said rigid member to prevent movement thereof under one condition, to permit movement thereof under another condition, and to limit movement of the rigid member under the influence of said working tool, and a cushion for yieldingly resisting movement of said rigid member and the flexible bed under the last-mentioned condition.

2. In a machine of the character described, in combination, a flexible bed fastened at one end and having its opposite end free to move, means connected with said free end to place the flexible bed under tension and to maintain the latter substantially uniform, a rigid member located under said flexible bed and coöperating therewith to move bodily with the flexible bed under the action of a working tool, means coöperating with said rigid member to prevent movement thereof under one condition, to permit movement thereof under another condition, and to limit movement of the rigid member under the influence of said working tool and means for yieldingly resisting movement of said rigid member and the flexible bed under the last-mentioned condition.

3. In a machine of the character described, in combination, a flexible bed, supports for said bed spaced apart and coöperating therewith to form a working section between said supports, means for placing the flexible bed under tension while permitting movement of the said working section under the action of 125 130

an operating tool, a rigid member located between said uprights and extended substantially the length of said working section to coöperate with said flexible bed and movable bodily for its entire length under the influence of said tool to maintain the contour of the working section the same irrespective of the place in the length of the working section with which the operating tool is engaged, and means located between said supports for yieldingly resisting bodily movement of said rigid member under the influence of said tool.

4. In a machine of the character described, in combination, a stationary frame provided with uprights spaced apart, devices supported by said uprights, a flexible strip extended over said devices to form a working section and having one end fixed and its opposite end movable, means connected with said movable end for placing said strip under tension and maintaining the latter substantially uniform while permitting movement of said bed under the action of an operating tool, a rigid member coöoperating with the flexible strip between said uprights and bodily movable with said strip under the influence of said operating tool, and means for permitting said rigid member to be moved bodily under the influence of said operating tool and for resisting said movement.

5. In a machine of the character described, in combination, a flexible bed, means for placing the same under tension while permitting movement of said bed under the action of an operating tool, and means coöperating with the underside of said bed between its ends to yieldingly resist movement of the flexible bed under the influence of said tool while maintaining the contour of the flexible bed the same irrespective of the

place in the length of the said bed with which the said operating tool is engaged.

6. In a machine of the character described, in combination, a flexible bed, uprights spaced apart for supporting said flexible bed and forming a working section thereof between said uprights, means for placing said flexible bed under tension while permitting movement of the working section under the action of an operating tool, a plate located between said uprights and extended substantially the length of the working section to coöperate therewith and movable bodily for its entire length with said working section under the influence of the operating tool to maintain the contour of the working surface of the bed the same irrespective of the place in the length of the working section with which the operating tool is engaged, and a cushion located between said uprights and substantially at the center of said working section and coöoperating with said rigid member to yieldingly resist bodily movement of the latter and of said working section.

7. In a machine of the character described, in combination, a flexible bed, uprights spaced apart to support said bed and form a working section, mechanical means for yieldingly supporting the bed between the ends of its working section and to resist movement of the bed under the action of an operating tool, and rigid means interposed between said working section and said mechanical means for placing the portions of the bed between the operating tool and the rear support for the bed in the same inclined position irrespective of the position of said tool.

In testimony whereof, I have signed my name to this specification.

LEWIS F. CUTLER.
